UNITED STATES PATENT OFFICE.

MARTIN S. MILLARD, OF KANSAS CITY, MISSOURI.

REFRIGERATOR.

SPECIFICATION forming part of Letters Patent No. 404,854, dated June 11, 1889.

Application filed August 18, 1888. Serial No. 283,110. (No model.)

To all whom it may concern:

Be it known that I, MARTIN S. MILLARD, a citizen of the United States, residing at Kansas City, in the county of Jackson and State 5 of Missouri, have invented certain new and useful Improvements in Refrigerators; and I do hereby declare the following to be a full, clear, and exact description of the invention, such as will enable others skilled in the 10 art to which it appertains to make and use the same.

My invention relates to an improvement in refrigerators.

The object is to provide for the retention of 15 the condensed vapor and drip from the ice and its removal without its entering the cold-air chamber.

A further object is to provide for regulating the drafts of air within the cooler and for 20 cleansing the pans.

With these ends in view my invention consists in certain features of construction and combinations of parts, as will be hereinafter described, and pointed out in the claims.

25 In the accompanying drawings, Figure 1 is a view in front elevation, the main door being open, showing the inside base-door closed. Fig. 2 is a view in rear elevation, the back casing being removed to show the interior of 30 the refrigerator. Fig. 3 is a view in vertical transverse section through line $\alpha\alpha$ of Fig. 1, and Fig. 4 is a view in detail of one side of the pan-rack.

The casing of the refrigerator consists of a 35 front, back, and two ends separable from each other and from the bottom and top. The bottom A and top A' are each provided with a groove a , preferably formed by a marginal bead a' and the outer edge a^2 of the thick wall 40 of the refrigerator. The grooves a are intended to receive the top and bottom edges of the side and end sections of the casing, and also to receive the upper and lower ends of V-shaped corner-moldings a^3 , which serve to 45 bind the sides and ends of the refrigerator firmly together.

The walls of the refrigerator are formed of a frame-work B, two inches thick (more or less) and having on both inside and outside 50 of it a layer of sheathing-paper b , or paper prepared in any well-known and suitable manner for the purpose, forming between the

walls of paper and within the frame B a dead-air chamber. Inside the paper layer b is a wood sheathing b' , and outside the outer paper layer are two thicknesses of sheathing b' , separated from each other by a third paper layer b . The wall thus formed is an effective non-conductor; but for small sizes and where it is desirable to make the walls quite thin 55 packing may be inserted in the dead-air chamber. The ice-chamber is provided, as is usual, in the upper portion of the refrigerator, and is surrounded partially or wholly by a rack C, provided with uprights c , spacing it from 60 the wall and affording room for the free circulation of the air around it. The bottom of the ice-chamber is also provided with a rack D, which is supported at its edges upon narrow drip-pans d d' . The drip-pans d d' are 65 made to interlock at the corners, preferably by shortening the side pans d the widths of the end pans d' , and the zinc, galvanized iron, or other suitable material which forms the linings of the pans or the pans themselves 70 are turned upward against the inner walls of the refrigerator to form a flashing, as shown at d^2 . The pans d d' are supported upon a suitable frame-work E, which rests at its ends upon suitable cross bars or cleats e . A door 8c F is provided at one end of the ice-chamber, through which the ice is passed into the 75 chamber.

Immediately below the floor of the ice-chamber there is formed a roof for the cooling-chamber, as follows: A pair of stringers G, provided on their upper faces with ratchet-like notches g , are secured at their opposite ends to the end walls of the refrigerator and extend along in proximity to the side walls of 80 the same. The long sides of the notches g form seats for a series of transverse drip-pans H, which are arranged therein after the manner of window-blind slats. The lower edges and one end of each pan H is provided 85 with an upwardly-extending flange h , and when the sheet-metal lining of the pan is in position thereon a trough is formed having one end closed. The bases of the pans H are 90 preferably of wood and are provided with cross-cleats h' , to prevent warping and splitting, the said cleats h' also being projected at their lower ends, forming retaining-lugs h^2 , which catch under pins h^3 in the sides of the 95 100

stringers and lock the pans in their positions on the stringers. The sheet-metal linings of the pans H are not exposed at any point on the under side of the pans.

5 When the pans H are resting normally on their seats, the lower edge of one pan abuts against the bottom of the upper edge of the next succeeding pan, thereby forming a closed roof or ceiling for the cooling-chamber. There 10 are, however, arranged underneath the ends of each pan arms I, pivoted to the inner faces of the stringers and adapted to swing up against the bottom of the pans and tilt them into more or less upright positions, forming 15 a greater or less opening through the roof for the circulation of air from the cooling-chamber below to the ice-chamber above, and vice versa. The pivoted arms I may be joined in series by a connection i, so that the pans may 20 be operated simultaneously.

The narrow pans d d', hereinbefore referred to, are arranged to shed the water into the pans H, and the latter are slightly higher at their closed ends, so that they shed the water 25 toward their open ends, where it is received into a narrow drip-trough K, arranged along the side of the refrigerator and provided with a spout k, which leads the water through the bottom or side of the refrigerator to a suitable waste-conduit.

A valve L is arranged at one end of the series of pans H, to open and close communication between the cooling and ice chambers, and immediately beneath the opposite end of 35 the series an inclined guide k' is provided to direct the currents of air from the wall of the cooling-chamber to the pans H. The condensation of vapors and the moisture which rises in the air from the cooling-chamber are 40 thus caused to take place above the cooling-chamber, and the waters of condensation, as they flow from the base of the ice-chamber, purify the air. A dry cold pure air is thus secured in the cooling-chamber.

45 The front of the refrigerator is provided with a main door M, to afford access to the interior of the cooling-chamber, and an inner base-door, which is half the height of the main door, (more or less,) and which serves 50 to prevent the escape of the cold air at the base. There is also provided a sub-compartment N in the corner of the cooling-chamber, to receive such articles as may be wanted for frequent use or to which access is desirable. The front of the compartment N preferably projects outwardly from the front of the refrigerator, as shown at n, and is provided with a trap-door or hinged cover O.

The rear of the compartment N communicates with the cooling-chamber through a hinged door o, and the latter is connected with the door O by a rod o', so that when the door O is raised the door o will be closed and the compartment N shut off completely from 65 the cooling-chamber, but when the door O is

closed the door o will be opened and its interior exposed to the cold air of the cooling-chamber. Any considerable rise of temperature in the cooling-chamber is thus prevented during the frequent opening of the compartment N. The front of the refrigerator is also provided over the compartment N with a large window P, arranged to slide up and down, and balanced by weights, as is usual in ordinary windows. The window P is formed 75 by several layers of insulated material to form a non-conductor, and is provided with one or more lights p, of double glass, to furnish light to the person who may be inside.

The window P furnishes an opening through 80 which large articles may be stored or removed without opening the main door.

As thus constructed, the refrigerator may be knocked down and packed in a small compass for transportation, and may be set up 85 for use with the greatest facility. It may be constructed as a large storage-refrigerator for wholesale and retail dealers in meats and produce, as a family refrigerator, or in the form of a refrigerator-car.

It is evident that slight changes in the form and arrangement of the several parts may be resorted to without departing from the spirit and scope of my invention, and hence I do not wish to limit myself to the construction 95 herein set forth, strictly; but,

Having fully described my invention, what I claim as new, and desire to secure by Letters Patent, is—

1. In a refrigerator, the combination, with a 100 suitable support provided with inclined seats and laterally-extending projections, of a series of drip-pans seated upon the support and provided with lugs adapted to catch under said lateral projections on the support and lock 105 the pans in position, pivoted arms for tilting said pans, and a rod connected to said arms for operating them, substantially as set forth.

2. In a refrigerator, the combination, with a suitable support provided with inclined 110 seats and with laterally-extending projections, of a series of drip-pans seated upon the support and provided with lugs or projections adapted to catch under the said lateral projections on the support and lock the pans 115 in position, substantially as set forth.

3. In a refrigerator, the combination, with a series of overlapping and contacting drip-pans forming a closed roof or ceiling for the cooling-chamber, of a valve at one end of the 120 series to open or close communication between the ice and cooling chambers, substantially as set forth.

In testimony whereof I have affixed my signature in presence of two witnesses.

MARTIN S. MILLARD.
